UNITED STATES PATENT OFFICE.

EUGENE E. P. TRUESDELL, OF BELVIDERE, ILLINOIS.

TWO-WHEELED VEHICLE.

SPECIFICATION forming part of Letters Patent No. 297,955, dated April 29, 1884.

Application filed February 23, 1884. (No model.)

To all whom it may concern:

Be it known that I, EUGENE E. P. TRUESDELL, a citizen of the United States, residing in the city of Belvidere, in the county of Boone 5 and State of Illinois, have invented a new and useful Improvement in Two-Wheeled Vehicles, of which the following is a specification.

This invention relates to a class of vehicles known in the trade as "road-carts;" and its 10 object is to adjust the thills relatively with the body to adapt the vehicle to horses varying in height without materially varying the horizontal position of the body or seat of the vehicle. It consists of pillow-blocks to connect 15 the thills with the axle-tree, produced in segment form, made adjustable within each other, and clamping-bolts to fix the parts in their adjusted position; also, the transverse corrugations of the contiguous faces of the pillow-blocks, for the double purpose of readily 20 determining the position of the adjustment and to prevent accidental displacement of the parts, all of which is represented in the accompanying drawings, in which—

25 Figure 1 is a side elevation of such portions of a two-wheeled road-cart as are necessary to illustrate my invention. Fig. 2 is a plan view of such portions of one side of a two-wheeled road-cart as are necessary to illustrate 30 my invention in its application; and Fig. 3 is a lengthwise vertical central section of my improvement on an enlarged scale on dotted line *x*, Fig. 2.

In the figures, A represents a portion of a 35 carrying-wheel of a two-wheeled road-cart, B a portion of the axle-tree, C a spring, D a spring-bar, and E a portion of the body-supporting loops, all of which are in every particular substantially the same as like parts in like 40 vehicles now in use; and their connections and purpose are substantially the same as the connections of like parts in like or similar vehicles now in use, and to be found in the trade.

45 At *a* is represented the bed portion of a two-part pillow-block of segment form, fitted with a prominence, *b*—in this instance of V form—rising centrally from its concave side, and extending transversely across the face of the block. One of these bed portions *a* is placed 50 upon the axle-tree toward the end portions thereof, inside of the wheels, in position to sup-

port the thills. These bed portions are fixed in position by means of staple-formed stirrup *c*, fitted to span the block on each side of the 55 axle-tree, and are gained or let into the upper face of the block to conform to the concave surface thereof. The lower end portions of the stirrups *c* are screw-threaded, and extend through clamping-plates *d*, placed on the under face of the axle-tree, and by means of screw-nuts *e* upon the depending ends of the stirrups serve to fix the bed portions *a* of the pillow-block securely in place on the axle-tree. The end portion of the bed portion *a* of the 60 pillow-block is centrally slotted lengthwise, as represented at *h*, to receive suitable clamping-bolts.

At *i* is represented the upper portion of the two-part pillow-block, which is of segment 70 form, having its outer surface produced on the same curve as the inner surface of the bed portion *a*, in such a manner that its outer curved surface shall engage the inner curved surface of the bed portion. This upper portion, *i*, is 75 provided, centrally, on its convex surface with a series of corrugations, *k*, of V form, extending transversely across its face. These corrugations *k* are of proper size to receive the V-formed prominence *b* on the bed portion of 80 the pillow-block, and serve to determine the position of the adjustment of the respective sides and to prevent accidental displacement.

At *l* is represented a bracket-support of the thills, having its central portion centrally fixed 85 to the concave surface of the upper portion, *i*, of the pillow-block by means of a screw-bolt, *m*, or otherwise.

At *n* are represented clamping-bolts, which are passed through the bracket-support of the 90 thills, through the upper portion of the pillow-block, and through the slots *h* in the lower portion, *a*, of the pillow-block, and by means of suitable screw-nuts, *o*, serve to clamp the two 95 portions of the pillow-block and the bracket-support of the thills in their adjusted position.

At *F* are represented thills, which may be of any suitable known form, and are connected forward of the axle-tree by means of a transverse bar, *H*, in the usual manner. The rear 100 ends of the thills rest upon the uprising arms of their bracket-supports, to which they are firmly secured by means of screw-bolts *p*, passed through the parts.

From the foregoing it will be seen that if the screw-nuts *o* of the clamping-bolts *n* are slackened or unscrewed sufficient to permit the upper portion of the pillow-block to pass over the *V*-formed prominence *b* of the lower portion of the pillow-block the thills may be adjusted from their position in the solid lines in Fig. 3 to their dotted-line position, either up or down or in any intermediate position within the capacity of the device, to adapt the vehicle to horses varying in height, to maintain the horizontal position of the body mounted thereon.

This device is also capable of use for the purpose of changing the position of the body 15 of the vehicle mounted thereon, to incline it either forward or rearward relatively with the thills. This adjustment is accomplished in the same manner and by the same means that the thills are adjusted higher or lower, as 20 shown in the dotted lines.

In the foregoing I have described and shown the prominence *b* in the bed portion of the pillow-block as of *V* form, and the corrugations *k* in the upper portion of a corresponding *V* form; but, instead of the *V* form, other known 25 forms may be employed and still be within the scope of my invention. Instead of the separate upper portion, *i*, of the pillow-block and the bracket-support *l*, these parts may be produced in one piece, in which construction the 30 use of the center bolt, *m*, will not be required.

For the purpose of producing a complete vehicle in connection with my improvements, the several parts necessary not herein shown or described may be any of the known forms 35 of such necessary parts, and may be applied in any known manner.

I claim as my invention—

1. The combination, with the axle-tree and with the thills, of a two-part pillow-block of 40 segment form, made adjustable within each other, substantially as and for the purpose set forth.

2. The two-part pillow-blocks of segment form, corrugated on their meeting surfaces 45 and made adjustable in the direction of their length to vary their relative positions, substantially as and for the purpose set forth.

3. The combination, with the two-part pillow-blocks of segment form, made adjustable 50 within each other, of clamping-bolts to fix the parts in their adjusted position, substantially as and for the purpose set forth.

4. The combination, with the axle-tree and with the thills, of a two-part pillow-block of 55 segment form, and a bracket-support to the thill, constructed and arranged to operate substantially as and for the purpose set forth.

EUGENE E. P. TRUESDELL.
